UNITED STATES PATENT OFFICE.

LOUIS KESSLER, OF CHICAGO, ILLINOIS.

FILLER TUBE.

Application filed November 12, 1921. Serial No. 514,837.

To all whom it may concern:

Be it known that I, LOUIS KESSLER, a citizen of the United States, residing at Chicago, in the county of Cook and State of Illinois, have invented certain new and useful Improvements in Filler Tubes, of which the following is a description.

My invention belongs to that general class of devices known as filler tubes, and particularly relates to an improved safety tube and closure for the same.

The invention has among its objects the production of a device of the kind described that is safe, simple, efficient, durable, compact and satisfactory for use wherever found applicable.

The invention has particularly among its objects the production of a closure that may be used in connection with any suitable form of filler tube of filler opening of a receptacle, for closing the opening where the tank is filled, whereby excessive pressure in the tank may be relieved and where air may be admitted to fill the space formerly occupied by the liquid as said liquid is being drawn from the tank. By this last-mentioned means, namely, the admittance of air into the tank while the contents therein are being drawn off, the creating of a vacuum in the tank and the consequent impairing of discharge is prevented, as well as collapsing of the tank, and at the same time the escape of gas from the tank due to evaporation is prevented. Danger of the tank contents exploding is entirely done away with.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a top plan view of my device;

Fig. 2 is a section taken substantially on the line 2—2 of Fig. 4;

Fig. 3 is a section taken substantially on the line 3—3 of Fig. 4;

Fig. 4 is a longitudinal section through my device;

Fig. 5 is a fragmentary front view of my device; and

Fig. 6 is a section taken substantially on the line 6—6 of Fig. 4.

In the drawings, wherein I have illustrated the preferred embodiment of my invention, there is shown a tank or other receptacle 1 adapted to contain liquids, and having a filling opening 2. My device is intended to cooperate with said tank at its filling opening to permit the filling thereof, to prevent flame entering the tank, to relieve excess pressure within the tank and to permit the admittance of air to the tank as the contents thereof are drawn off. A pair of coaxial spaced tubes 3 and 4 are shown as 70 extending into the tank, said tubes being perforated in their side walls, the outer tube being perforated for substantially its entire length, and the inner tube 4 being perforated from the bottom to a slight distance below the upper perforations of the outer tube. These tubes may be constructed of any suitable material, having apertures therethrough, and in the present instance I provide the outer tube with a fine 80 wire gauze 5 at the interior, a gauze of approximately 110 meshes to the inch being preferred.

The closed or lower end 7 of the inner tube may be supported and rest on the 85 closed end 8 of the outer tube, if desired. When the tubes are provided with a solid, imperforate bottom wall, there is no danger of unauthorized persons inserting a stick, or the like, into the tank through the bottom walls of the tubes.

A closure member comprising a plate 9 having a pair of annular, radially-spaced flanges 10 and 11 projecting from one face thereof, is arranged to cooperate with the 95 filling opening of the tank and to carry the tubes 3 and 4, the flange 10 being preferably screw threaded so as to detachably connect with the threaded flange of the opening of the tank, and the flange 11 is 100 also preferably screw threaded to detachably receive the threaded end of the outer tube 3. The plate 9 is extended radially inwardly, past the flange 11, to form an

annular seat 12 engageable with the outer open upper end of the tube 4, spacing it from the tube 3. The seat 12 may be brazed or soldered to the top of the tube 4, or may be otherwise joined thereto. The plate 9 has one or more ports or openings 13 therethrough, between the inner and outer tubes 4 and 3.

A cap 14, which is shown in the form of a disk member, is adapted to be positioned on the plate 9 to control the openings of both of said tubes, said cap covering the apertures 13 and having a check valve 15 therein. The check valve comprises a chamber 15' having a duct 21 therethrough. A movable valve member 16 is engageable with said valve seat 17 formed in the disk, said member 16 being supportably carried by a member 18 pressed upwardly against the valve seat by a coil spring 19, said coil spring being adjustably and removably held in place by a part 20. It will be noted that the parts 18 and 20 also have bores therethrough communicating with the interior of the tubes, and with said bore 21 communicating with the atmosphere, whereby air may pass from the atmosphere through the check valve and into the tubes and the tank.

A flange 22 is provided on the plate 9, projecting in a direction opposite to that of the flanges 10 and 11, the flange 22 being less than a complete annulus and preferably semi-annular, as shown in Fig. 1. A pair of arms 23 are carried by said plate 9 rearwardly of said flange 22, and projecting beyond the periphery of the plate 9. A rod or pin 24 is pivotally secured between said arms 23, said rod carrying a lever 25 apertured at its free end as at 26. The valved disk 14 is pivoted to the lever 25 at 27, and a spring 28 is arranged to cooperate with the lever 25 to exert a pressure upon it to normally keep it in the position shown in full lines in Fig. 4, or, in other words, the spring 28 normally keeps the disk 14 tightly closed on its seat to close the open ends of the tubes 3.

In case of any pressure in the tank, caused for any reason whatever, when the same reaches the point where it overcomes the spring 28, the closure disk 14 may lift slightly against said spring pressure so that the pressure within the tank may be relieved through the ports 13, after which the disk drops back into position, closing the receptacle. As the liquid is drawn off from the tank, air may enter through the check valve 15 thereby preventing a partial vacuum within the tank, that will interfere with the operation. It is impossible for any flame to get through the gauze covering the tubes and igniting the contents of the tank. The device is, therefore, non-explosive. The device therefore is an efficient safety device,

65 preventing the contents of the tank from becoming ignited and exploding.

Owing to the close mesh of the gauze 5, any water in the gasoline or fluid will not pass through the tubes and enter the tank. As the gasoline or fluid is poured into the tank through the tubes, the water, if it accumulates, will flow upwardly between the tubes and out through the openings 13, the incoming gasoline or fluid causing this action.

70 In order to lock the closure member 14 against tampering by unauthorized persons, there is shown a locking arm 29 pivotally secured to a projecting lug 30 at the side of the plate 9 diametrically opposite to its pivotal connection with the lever 25. The locking arm 29 is preferably yoked and is bent to the form of a bell-crank lever, whereby its leg 31 will limit the pivotal movement 75 of the locking arm, by abutting against the edge of the plate 9, as shown in the drawings, in which position the top edge of the lever will be a slight distance from the free end of the yoke, so as to permit a little lift or play therebetween. The free end of the locking arm is provided with an aperture 32 which is adapted to cooperate with the aperture 26 at the free end of the lever, to receive a padlock or the like 33, to lock said parts in position. It will be noted that even when the parts are locked in position, as shown in Fig. 4, there is permitted a slight lifting movement of the lever 25 and the disk 14 carried thereby relative to the open ends of the tubes 3 and 4, so that any excess of pressure within the tank may be relieved with the padlock in position, by the slight unseating 80 of said disk.

85 Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

100 What I claim as new and desire to secure by Letters Patent is:

1. A filling tube of the kind described, comprising a pair of spaced inner and outer tubes perforated in their side walls, and a closure cap for the open end of both of said tubes, said inner tube resting on the bottom 105 of the outer tube.

115 2. A filling tube of the kind described, comprising a pair of spaced inner and outer tubes perforated in their side walls, and a valved closure cap for the open ends of both of said tubes, said inner tube extending to the bottom of the outer tube and resting thereon.

120 3. A filling tube of the kind described,

- comprising a pair of spaced inner and outer tubes perforated in their side walls, and with an imperforate bottom, and a valved closure cap for the open end of both of said tubes, said inner tube extending to the bottom of the outer tube and resting thereon.
4. A filling tube of the kind described, comprising a pair of inner and outer tubes perforated in their side walls and each having one of their ends imperforate, the inner tube engaging with and resting on the imperforate end of the outer tube, and a closure cap for controlling the end openings of both of said tubes, and spacing said tubes apart.
5. A tank closure of the kind described, comprising a member having an axial bore and provided with a pair of radially spaced annular flanges projecting from one face thereof and spaced radially outwardly of said bore, whereby tubes may be arranged to engage within said bore and the inner flange, the outer flange adapted for attachment to a tank, and closure means for controlling said bore.
6. A tank closure comprising a member having an axial bore and provided with a pair of radially spaced, annular flanges projecting from one face thereof and spaced radially outwardly of said bore, whereby tubes may be arranged to engage within said bore and the inner flange, there being openings provided in said member between said bore and inner flange, the outer flange adapted for attachment to a tank, and closure means for controlling said bore and said openings.
7. A tank closure comprising a member constructed for securing to a tank and having a central opening therethrough, a closure member arranged to fit over and control said opening, and means for releasably holding said closure in place, including a lever pivoted to said first-mentioned member and carrying said second-mentioned member, and locking means engageable with the free end of said lever to normally prevent the unseating movement of said second member, although permitting it to be lifted slightly off its seat to relieve excessive pressure within the tank.
8. A tank closure comprising a member constructed for securing to a tank and having a central opening therethrough, a closure member arranged to fit over and control said opening, and means for releasably holding said closure member in place, including a lever pivoted to said first-mentioned member and carrying said second-mentioned member, means for resiliently maintaining said second-mentioned member on its seat, and locking means on said first-mentioned member and engageable with the free end of said lever, with play therebetween, to normally prevent the full unseating movement of said second member, although permitting it to be lifted slightly off its seat to relieve excessive pressure within the tank.
9. A tank closure comprising a cap having a pair of radially spaced annular flanges depending therefrom, one of said flanges engageable with an outer tube, the other of said flanges engageable with a tank opening, the top of said cap extending radially inwardly past said inner flange to form a seat for an inner tube and space it from said outer tube, said tubes open at their upper ends, a lever pivotally carried by said cap, a disk pivotally secured to said lever and controlling the open ends of said tubes, a locking link pivoted to said cap, said link and lever having apertures at their free ends through which locking means may be inserted to permit a limited play between said link and lever so that the disk may be lifted slightly off its seat when said locking means are in place.
10. A filling tube of the kind described, comprising a pair of inner and outer tubes, said tubes open at one end, means for carrying said tubes comprising a member having a pair of radially spaced annular flanges, one of said flanges engageable with a tank opening, the other of said flanges engageable with the outer of said tubes, said member also provided with a radially extending portion engageable with said inner tube to provide a seat therefor to space said tubes apart, a disk seated on said member to control the open ends of said tubes, a check valve in said disk, a lever pivotally carrying said disk and pivotally connected to said member, said lever having an aperture in its free end, a locking arm pivotally connected to said member and adapted to abut thereagainst to limit its pivotal movement, said locking arm having an aperture therethrough adapted to cooperate with the aperture in the free end of the lever, and locking means insertable through said cooperating apertures, said lever and locking arm having a slight play therebetween to permit said lever and disk to unseat when the pressure within said tank becomes excessive.
11. A filling tube of the kind described, comprising a pair of spaced inner and outer tubes with one end closed and the other open, and a closure cap for controlling the open ends of both said tubes, said cap having openings intermediate said tubes the outer tube having openings in its side wall substantially along its entire length, and the inner tube having openings in its side wall from its bottom to within a short distance of the uppermost openings in the other tube, the openings in both of said tubes communicating with said openings in the cap.
12. A filling tube of the kind described, comprising a pair of spaced inner and outer tubes with one end closed and the other open, and a closure cap at the open ends of

both of said tubes and having openings therethrough communicating with the space between said tubes, the outer tube having openings in its side wall substantially along its entire length, and the inner tube having openings in its side wall from its bottom to within a short distance of the uppermost openings in the other tube.

In testimony whereof, I have hereunto signed my name in the presence of two subscribing witnesses. 10

LOUIS KESSLER.
